US0D1055073S

(12) **United States Design Patent** (10) **Patent No.:** **US D1,055,073 S**
(45) **Date of Patent:** **** Dec. 24, 2024**

(54) **PORTABLE COMPUTER**

(71) Applicant: **Lenovo (Beijing) Limited**, Beijing (CN)

(72) Inventor: **Xi Chen**, Beijing (CN)

(73) Assignee: **Lenovo (Beijing) Limited**, Beijing (CN)

(**) Term: **15 Years**

(21) Appl. No.: **35/518,019**

(22) Filed: **Jun. 21, 2023**

(80) **Hague Agreement Data**

Int. Filing Date: **Jun. 21, 2023**

Int. Reg. No.: **DM/230552**

Int. Reg. Date: **Jun. 21, 2023**

Int. Reg. Pub. Date: **Aug. 4, 2023**

(30) **Foreign Application Priority Data**

Dec. 21, 2022 (CN) 202230853757.0

(51) **LOC (14) Cl.** **14-02**

(52) **U.S. Cl.**

USPC **D14/440**; D14/315

(58) **Field of Classification Search**

USPC D14/315-327, 344-347, 353-355, D14/439-441, 444-446; D3/900, 902

CPC G06F 1/1641; G06F 1/1681

See application file for complete search history.

(57) **CLAIM**

The ornamental design for a portable computer as shown and described.

DESCRIPTION

The patent or application file contains at least one drawing executed in color. Copies of this patent or patent application publication with color drawing(s) will be provided by the Office upon request and payment of the necessary fee.

1.1: Front view

1.2: Back view

1.3: Left view

1.4: Right view

1.5: Top view

1.6: Bottom view

1.7: Perspective view

The portions of the portable computer, shown in deemphasized half-tone shading and surrounded by broken lines, form no part of the claimed design.

1 Claim, 7 Drawing Sheets
(2 of 7 Drawing Sheet(s) Filed in Color)
